UNITED STATES PATENT OFFICE.

ERNST G. K. ANDERSON, OF CHICAGO, ILLINOIS, ASSIGNOR TO APPLETON ELECTRIC COMPANY, A CORPORATION OF ILLINOIS.

CONTROLLING SWITCH FOR SPOTLIGHTS AND THE LIKE.

Application filed February 10, 1926. Serial No. 87,285.

The present invention, specifically considered, relates to spotlights of the kind that have a rotatable operating stem on which is supported a switch for turning the light off and on, and it has for its objects: first, to produce a simple and novel switch in the shape of a collar adapted to surround a stem or shaft and be capable of attachment, removal or adjustment by a movement lengthwise of the shaft; second, to produce a simple and novel switch adapted to be mounted on a rotatable shaft or the like, to connect together a stationary conductor and a conductor rotatable with the shaft; third, to produce a simple and novel connection between a conductor extending through the interior of a hollow shaft and a switch mounted on the exterior of the shaft.

20 The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a side elevation of a spotlight and a fragment of the support on which it is mounted, having my improved switch applied to the operating stem; Fig. 2 is a section, on an enlarged scale, taken on a vertical plane passing through the switch at the long axis of the stem; Fig. 3 is a section taken on line 3—3 of Fig. 2; Fig. 4 is a section taken on line 4—4 of Fig. 2, looking in the direction of the arrows; Figs. 5 and 6 are two similar sections taken approximately on line 5—5 of Fig. 2, Fig. 5 showing the switch closed and Fig. 6 showing the switch open; Fig. 7 is a section taken approximately on line 7—7 of Fig. 5; Fig. 8 is a section taken approximately on line 8—8 of Fig. 6; and Fig. 9 is a side view of the disc-like actuator for the movable arm of the switch.

Referring to Fig. 1 of the drawings, 1 represents a spotlight of any usual or suitable construction mounted on a post or other supporting member 2 through which extends a hollow actuating stem 3 having on the end a detachable handle 4. Current is supplied to the lamp through a cable 5 that may be anchored to the supporting member 2, and a second cable 6 that extends

through the tubular stem and is adapted to be electrically connected with the cable 5 by my improved switch mechanism.

The switch mechanism is enclosed within a casing comprising two cup-shaped members 7 and 8. The member 7 has a central opening through the bottom of the cup just large enough to receive the stem. The diameter of the cup 8 is smaller than that of the other cup so that, when the two members are placed together, with their mouths toward each other, the smaller cup may enter the larger one. The member 8 has a sleeve-like part 9 projecting outwardly from the bottom wall thereof, the internal diameter of the part 9 being the same as the external diameter of the stem so that the stem may be slipped into the sleeve. A second sleeve 10 opens out from the side of the sleeve 9, and into this sleeve is secured a long bushing 11 around which a clamp 12 may be placed to fasten the same to the support 2. The cable 5 extends up through the bushing 11 and the sleeve 10 into the interior of the cup 8. Within the cup 8 is arranged a block 13 of insulating material that preferably has an arc-shaped guard 14 extending partially across the inner end of the sleeve 10 so as to overlie the bend in the cable 5, whose upper end is directed laterally and passed through a hole 15 in the block 13, parallel with the long axis of the same. In the outer face of the block 13 is an annular groove 16 within which lies a contact ring 17 to which the exposed end of the cable 5 is fastened, as best indicated at 18 in Fig. 2. The block is thicker than the depth of the cup 8, and that part which projects from the cup is enlarged in diameter, as indicated at 19, so as to fit within the larger cup 7. In the cup 7 is a block 20 of insulating material whose thickness is considerably less than the depth of the cup. A small tube 21 of conducting material extends through the block 20, parallel with the long axis of the same, and below the latter, this tube extending also through the bottom wall of the cup and being insulated from the latter. In the exposed face of the block 20 is an arc-shaped depression 22 within one end of which an end of the tubular member 21 lies. In this groove is a resilient contact finger 23 one end of which is fixed to the block by means of the tube 21 serving in the capacity of a rivet. The free end of the contact piece or finger is bent

105

110

upwardly and then downwardly to form an upward projection 24 shaped like an inverted V. When free to do so, this projection engages with the contact ring 17 in the block 13. In the space between the blocks 13 and 20 is a disc 25 of insulating material rotatable on the stem. As best shown in Fig. 9, the disc 25 has a long recess 26 cut into the periphery and, at the middle of this recess there is a further recess 27. As best shown in Figs. 7 and 8, there is a curved plate 28 set into the recess 27 and, overlying this plate, is a light plate 29 that fills the recess 26. A finger piece 30 extends through a slot 31 lying circumferentially with respect to the cylindrical wall of the casing 7 and through the plate 29 and is screw-threaded into the plate 28. By swinging the finger piece 30 around the axis of the stem, the disc 25 will be given a corresponding angular movement. The plate 29 is made of such a length that it will always cover the slot 31. The disc 25 has therein a hole 35 which, when the disc is at one end of its angular movement, lies opposite the projection 24 on the contact finger, and which is large enough to permit this projection to pass through the same and engage with the ring 17. As the disc is turned toward its other angular position, the trailing bounding edge for the hole 35 rides up on one inclined side of the projection 24, pressing the projection laterally and carrying it out of engagement with the co-operating ring. If desired, the disc 25 may be provided with a smaller hole or a slot 36, so located that when the disc reaches the other limit of its angular movement, the ridge of the projection will enter this smaller hole or notch and serve as a yielding lock to hold the disc against accidental displacement; the hole or slot being sufficiently small to avoid any possibility of metal contact between the projection and the co-operating ring.

The two cups are held together by a split resilient ring 37 that is snapped underneath a curved lip 38 extending around the mouth of the cup 7, so as to lie in front of a flange 8^a surrounding the mouth of the cup 8 and engaged with the front face of the enlarged portion 19 of the block 13 in the cup 8. The cup 7 is fastened to the stem by means of a screw 40 extending through the cylindrical wall of the cup and bearing against the periphery of the stem. Since the two cups are preferably made of sheet metal, the block 20 in the cup 7 is preferably provided with a metal bushing 41 surrounding the stem and in contact with the same, thereby permitting the fastening screw 40 to be threaded through this bushing instead of through the metal of which the cup is made.

The cable 6 extends from the lamp through the hollow stem, and is passed down through a slot 42 in the underside of the stem. On

the free end of the cable is a plug 43 adapted to fit snugly into the tube 21, but not so tightly as to prevent its withdrawal from this tube when a reasonable pulling force is applied thereto.

When the cable 6 is plugged to the switch, current will flow from the cable 5 to the cable 6 when the switch is closed, the path of the current being from the connection 18 of the cable 5 with the ring 17, through the ring, through the resilient contact finger 23, through the tube 21 and into the plug 43. When the switch is open the flow of current is interrupted by reason of the fact that the resilient contact finger is out of engagement with the co-operating contact ring.

In the use of the spotlight, the tubular stem being turned back and forth around its long axis from time to time, it will be seen that the cup 7, together with the resilient contact finger and the controlling disc 25 turn with the stem, while the cup 8 with its block 9 and contact ring 17 remain stationary. In other words, the positions of the actuating handle 4 for the spotlight and the finger piece 30 for the switch do not change relatively to each other on account of a turning movement of the spotlight stem; but the finger piece for actuating the switch always lies in the same relation to the actuating handle 4, both when the switch is open and when it is closed, irrespective of the absolute position of the handle 4. Also, the leading-in cable 5 is anchored in a stationary position, so that no slack need be provided in the cable to compensate for the angular movement of the stem during the operation of the spotlight.

In order to assemble the switch on the stem, the operating handle 4 is detached and the switch parts, with the cable 5 connected thereto are slipped endwise upon the stem and slid along the same to the point where they are to remain; the free end of the cable 6 being withdrawn into the stem through the slot 42. When the switch has been properly located lengthwise of the stem, and has been bodily adjusted angularly of the same, the holding screw 40 is turned to lock the cup 7 to the stem, and the clamp 12 is applied to the sleeve or bushing 11 to anchor the latter to the post 2 or other stationary support. The end of the cable 6 is then brought out through the slot 42 and the plug 43 is inserted in the tube or socket 21.

It will thus be seen that I have produced a simple and novel switch device consisting of a few simple parts, constructed and arranged to connect together two conductors that are movable relatively to each other, without requiring any slack in the conductors to compensate for such relative movements. It will also be seen that I have produced a simple and novel switch in the shape of a collar-like structure that may be

slipped endwise along a shaft or tube and be adjusted angularly of the latter.

Furthermore, the two sections of the switch may be adjusted angularly independently of each other, so that the stationary cable may be anchored at any desired angle, and the finger piece may be adjusted angularly of the stem of the lamp to bring it into the position which makes its operation 10 most convenient.

While I have illustrated and described with particularity only a single preferred form of my invention, I do not desire to be limited to the exact structural details thus 15 illustrated and described; but intend to cover all forms and arrangements which come within the definitions of my invention constituting the appended claims.

I claim:

20 1. A switch device comprising two members rotatable relatively to each other, and each provided with a terminal, contact pieces in said members adapted to be engaged with each other in any relative angular position 25 of said members to connect said terminals together, and an element movable with one of said members and also capable of movement independently thereof to control the engagement of said contact pieces with each 30 other.

2. A switch device comprising two annular members rotatable relatively to each other about their central axis, a contact piece in each member adapted to be engaged with 35 the contact piece in the other member in any relative angular position of said members, and an element rotatable with one of said members and capable also of independent movement relative thereto to control the 40 engagement of said contact pieces with each other.

3. In combination, a support, a cylindrical member mounted on said support so as to be rotatable about its long axis, a switch casing 45 surrounding said member and composed of two parts, one part of the casing being anchored to said support and the other part of the casing being secured to said member, a contact piece in each of said casing parts 50 adapted to be engaged with each other in any angular position of said member, and an element movable with the casing part that is secured to said member and also capable 55 of independent movement to control the engagement of said contact pieces with each other.

4. In combination, a cylindrical member rotatable about its long axis, a switch casing surrounding said member and divided 60 into two sections along a plane transverse to said axis, one of said sections being rotatable on said member and the other being secured to said member, a contact piece mounted in the said rotatable section of the casing and 65 extending angularly around the same, a con-

tact finger in the other section of the casing adapted to engage with said contact piece in any relative angular position of the casing sections, and means mounted in the casing section secured to the said member so 70 as to be rotatable therewith and also be capable of independent movements relative thereto to control the engagement of said finger with said contact piece.

5. In combination, a rotatable cylindrical 75 member, two cup-shaped switch casing sections surrounding said member and oppositely disposed to form a chamber between the same around said member, means for anchoring one section of the casing to a stationary support, means for securing the second section to said member, a switch device in said casing including a part mounted in and movable with each of the sections, and a switch controlling device carried by 80 said second section and capable of movement independently of the latter.

6. In combination, a tubular member rotatable about its long axis, a switch casing composed of two sections surrounding said 85 member and placed side by side thereon, one of said sections being loose on said member and the second section being secured to said member so as to be rotatable therewith, a switch device in said casing, a terminal associated with each section of the casing, a cable in said member, said member having a slot through the wall thereof in the vicinity of said casing, said cable extending through 90 said slot and having a part detachably connected to the terminal associated with the casing section that is secured to said member.

7. In combination, a tubular member rotatable about its long axis, a switch device 105 surrounding said member, said member having a slot through the wall thereof adjacent to said switch device, a cable within said member, said cable projecting through said slot at one end and having a part detachably connected to said switch device, the construction being such that said end of the cable may be withdrawn into the interior of 110 said member through said slot.

8. In combination, a support, a tubular 115 member mounted on said support for angular movements about its long axis, a switch device on said member, a conductor anchored to said support and connected to said switch device, said tubular member having 120 an opening through the wall thereof, said switch device having a terminal socket, and a conductor located within said member and having an end extended through said opening and provided with a plug adapted to fit 125 said socket.

9. In combination, a tubular member having a hole through its wall, a switch device surrounding said member and adapted to be 130 slipped on and off the same by a movement

in the direction of the length of said wall, a conductor arranged within said member and having an end extended through said hole, said end and said switch device having 5 cooperating elements for detachably connecting them together, and the parts being so proportioned that the said end of the conductor and its connecting element may be withdrawn into said member through said 10 hole.

10. A switch device comprising a casing composed of two cup-shaped members oppositely disposed and partly telescoped upon each other, said members being movable angularly relatively to each other, a contact ring mounted in and rotatable with one of 15 said members, a contact finger mounted in and rotatable with the other member, the finger tending constantly to engage said ring, an insulating plate mounted in the casing between the ring and the finger and having a limited angular movement with respect to that member containing the finger, 20 said plate having an opening therein to permit the finger to pass through the same, and 25

a part extending from said plate to the exterior of the casing to permit the plate to be turned.

11. A switch device comprising a casing composed of two cup-shaped members oppositely disposed and partly telescoped upon each other, said members being rotatable relatively to each other, a block of insulation in each member a disc of insulating material between said blocks, the aforesaid elements having registering central openings to receive a supporting shaft, a ring mounted on one of said insulating blocks, a contact finger on the other block tending constantly to engage said ring, said disc having an opening therethrough to permit the finger to extend therethrough and engage said ring, and means extending to the exterior of the casing whereby said disc may be turned a limited angular distance with respect to said finger.

In testimony whereof, I sign this specification.

ERNST G. K. ANDERSON.
